The ornamental design for a writing instrument, as shown and described.

DESCRIPTION

FIG. 1 is a front, left perspective view of a writing instrument showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof; and,

FIG. 8 is a left side perspective view of the writing instrument of FIG. 1, with the cap removed.

The broken lines in the figures are for the purpose of illustrating portions of the writing instrument that form no part of the claimed design.

1 Claim, 7 Drawing Sheets---
